UNITED STATES PATENT OFFICE.

CHARLES M. SNIDER, OF COLUMBUS, OHIO, ASSIGNOR TO THE JEFFREY MANUFACTURING COMPANY, OF COLUMBUS, OHIO, A CORPORATION OF OHIO.

SHEAVE WHEEL.

Application filed February 13, 1922. Serial No. 536,071.

To all whom it may concern:

Be it known that I, CHARLES M. SNIDER, a citizen of the United States, residing at Columbus, in the county of Franklin and State 5 of Ohio, have invented certain new and useful Improvements in Sheave Wheels, of which the following is a specification, reference being had therein to the accompanying drawing.

10 The present invention relates to certain new and useful improvements in sheave wheels, and particularly to that class of sheave wheel which is adapted to use with the endless cables of cable conveyors, and 15 power transmission installations where transmission blocks are clamped in spaced relation upon said cable.

It is the especial object of this invention to provide a wheel of the class described, 20 having improved removable cable supporting and driving members adapted to co-operate with the transmission blocks upon the cable, and which are adapted to convenient and expeditious adjustment to compensate for the elongation of the cable under 25 the strains of protracted service.

The devices by which I attain this object are fully set forth in the following specification, and illustrated in the accompanying drawings of which—

Fig. 1 is a side elevation of the preferred embodiment of my invention.

Fig. 2 is a sectional view taken along the line II—II of Fig. 1.

35 Fig. 3 is a detail on an enlarged scale of one of the cable supporting and driving members illustrated in Fig. 1.

Like numerals refer to similar parts in the several figures.

40 In the drawing, the numeral 1 refers to a wheel in the rim 2, of which are formed pockets 3 adapted to receive the transmission blocks 4 which are clamped in spaced relation upon the endless cable 5 in the manner common in cable conveyor practice. At 45 their ends 6, the pockets 3 are contracted to receive the cable supporting and driving members 7, and the side walls 8 of these pockets are pierced by transversely extending bolts 9 upon which said members are supported. Along the opposite lateral edges of the members 7, there are formed cable seats 10, adapted to support the cable 5, while both ends 11 of said members are

shaped to engage the transmission blocks 4 55 and afford them a fair bearing.

The apertures 12 in the members 7, through which project the supporting bolts 9, are arranged in a line parallel with, but spaced from the longitudinal center line 13 60 of the driving members in such manner that by turning one side or the other outwardly, the effective radius of the sheave 1 may be varied by an amount equal to the eccentricity of the apertures 12. 65

In practice, the wheels are commonly installed with the driving members 7 so turned as to produce a sheave of minimum radius, and after the cable has become elongated by the strains of service, the bolts 9 may be 70 removed, the members 7 turned other side out to increase the effective radius of the sheave, and the bolts 9 replaced to hold them securely in position.

By the devices above described, I have produced a cable sheave of simple and durable construction which may be conveniently and expeditiously adjusted to accurately fit the spacing of the transmission blocks upon the cable to drive it. 75

I claim:

1. In a cable sheave adapted to use with an endless cable having transmission blocks clamped in spaced relation thereon, the combination with a wheel, of pockets formed 85 in the periphery of said wheel, bolts extending transversely through the side walls of said pockets, and cable engaging members supported upon said bolts and adapted to engage the transmission blocks on 90 said cable, said members having a plurality of cable supporting surfaces differentially spaced from said supporting bolts, either of which may be turned outwardly to vary the effective radius of the sheave as and for 95 the purpose set forth.

2. In a cable sheave adapted to use with an endless cable having transmission blocks clamped in spaced relation thereon, the combination with a wheel, of pockets formed in 100 the periphery of the wheel, and cable engaging members supported in said pockets and adapted to engage the transmission blocks upon said cable, said members having a plurality of cable supporting surfaces 105 differentially spaced from the supporting means in said pockets either of which may be turned outwardly to vary the effective

radius of the sheave as and for the purpose set forth.

3. In a cable sheave adapted to use with an endless cable having transmission blocks clamped in spaced relation thereon, the combination with a wheel, of cable engaging members adapted to engage the transmission blocks on said cable, means to support said members upon said wheel, said mem-

bers having a plurality of cable supporting faces differentially spaced from said supporting means, either of which may be turned outwardly to vary the effective radius of the sheave as and for the purpose set forth.

In testimony whereof, I affix my signature.

CHARLES M. SNIDER.
